UNITED STATES PATENT OFFICE.

WILLIAM S. BOWMAN, OF ORANGEVILLE, PENNSYLVANIA.

PLAYING CARDS.

Application filed July 13, 1925. Serial No. 43,171.

To all whom it may concern:

Be it known that I, WILLIAM S. BOWMAN, a citizen of the United States, and resident of Orangeville, in the county of Columbia 5 and State of Pennsylvania, have invented certain new and useful Improvements in Playing Cards; and I do hereby declare the following to be a full, clear, and exact description of the invention, such as will enable others skilled in the art to which it appertains to make and use the same.

This invention relates to amusement games, and especially to games played with cards.

15 Specifically the invention relates to devices adapted for the play of card games having a certain educational value, when played by small children, said game involving a decided element of chance which renders it also attractive for adults.

One of the primary objects of the invention is the provision of a deck of cards equally divided into head cards and tail cards, as indicated by symbols carried on 25 the back of each card, the front faces of each of the cards carrying a representation of the front or rear portion of an animal which, when matched up with another card in the deck, forms a complete pictorial representation of such animal.

It is another object of the invention to include, with the pictorial representation of the animal carried on the face of the card, letters forming a portion of the name of 35 such animal.

A still further object of the invention is the provision, on the face of each card, of numbers or other designations indicative of the particular value of the card in playing 40 the game.

Other objects of the invention will be made apparent in the following specification, taken in connection with the drawings forming a part thereof.

45 In said drawings:

Fig. 1 represents the rear side of a tail card of the deck of cards used in playing the game.

Fig. 2 represents the rear side of a head 0 card.

Fig. 3 is a view of the face of one of the head cards, showing a buffalo head.

Fig. 4 is a view of the face of one of the tail cards, showing the rear portion of a 55 buffalo.

Fig. 5 represents the face of one of the head cards showing a camel.

Fig. 6 represents the face of a camel tail card.

Fig. 7 represents the face of a horse head 60 card.

Fig. 8 represents the face of a horse tail card.

Fig. 9 represents the face of a moose head 65 card.

Fig. 10 represents the face of a moose tail card.

Fig. 11 represents the face of a zebra head card, and

Fig. 12 represents the face of a zebra tail 70 card.

Now referring specifically to the drawings, it is to be stated that I have here chosen to illustrate the animals as shown, but it is obvious that the selection of the specific animals is arbitrary. Any other animals would answer the same purpose in playing the game, or the pictorial representation of birds or fishes might be substituted.

In playing the game I prefer to provide a 80 deck of 60 cards, of which 30 are head cards and 30 are tail cards, each head card being here shown as provided on its back with a pictorial representation of the front portion of a donkey, and the back of each tail card 85 being provided with a pictorial representation of the tail portion of a donkey.

The face of each head card is provided with a picture of the front portion of an animal, and the face of each tail card is illustrated 90 with a representation of the rear portion of an animal. Furthermore, the face of each head card carries, adjacent its right-hand edge, the first letters of the name of whatever animal may be partially pictured on the 95 card, while the face of each tail card carries, adjacent its left-hand edge, the remaining letters of the name of the animal of which the tail portion is shown.

I have arbitrarily chosen to provide 100 6 head cards which are exactly alike, as to the head portions and name portions shown thereon, and 6 tail cards which are exactly alike as to the tail portions and name portions shown thereon. Each card of the series of six however bears a different number, from 1 to 6, denoting the value of the card in playing the game. In other words there are 6 head cards for each animal, exactly like the cards shown in Figs. 3, 5, 7, 9 and 11, except that 110

the numbers, as shown in the upper left hand corner of the card varies from 1 to 6 on the successive cards, and the same is true of the tail cards. So that there are 6 "buffalo" head cards, each bearing the letters "BU," and the representation of the head portion of the buffalo, the numbers on the cards running from 1 to 6. Also each tail card of a series is the same as the other tail

5 card of that series, except for the number carried thereby. It is understood that there are also 6 head and 6 tail cards for each of the animals herein enumerated.

10 With a deck of cards as described many 15 games may be played which are interesting to adults and young people, and instructive to children. Certain of such games may be described as follows:

15 In playing games with the cards the combinations and values are made by placing head cards and tail cards side by side on the table and facing upwardly, the cards being so positioned that the portion of the animal shown on the face of the head card 20 will complement the portion shown on the other card to form an animal. If the animal so formed is made up of the head of one animal and the tail of another animal, and if the numbers on the head and tail cards 25 are different, it is called a "freak," and the name formed on the two cards will be a freak name, such as Zemal, or Burse, etc. Such a combination is of the lowest possible 30 value.

35 "Double freaks" are made by head and tail cards of different animals, each card bearing the same index number, and are next in value.

40 "Jacks" are made by head and tail cards of the same animal, but bearing different index numbers, and this combination represents the third highest value.

45 "Double-jacks" are formed by a combination of the proper face and tail cards of an animal, each card bearing the same numbers.

50 It is of course possible to assign other values to the combinations as above outlined, the above being merely representative. Any number of players from two to six may play, the partnership game being the better.

55 The cards are thoroughly shuffled, keeping the head and tail cards separated in shuffling and dealing, and care should always be observed to prevent mixing the head and tail cards. After shuffling, the 30 head and 30 tail cards are placed together in one stack, the head cards all facing downwardly, 60 and the tail cards upwardly. Each player is then dealt five tail cards from the top of the deck, the faces of said cards being exposed on the table in front of the player. The remainder of the deck is then turned over and five head cards are dealt to each

player, who holds them in his hand unexposed. The balance of the deck is then laid aside and temporarily unused.

With four players in a game the first player takes a head card from his hand and 70 combines it with a tail card on the table in front of him to form a "freak" or a "jack." Assuming that one of the cards bears the number 3, and the other the number 5, the player has made an "8 freak" or an "8 75 jack" and so declares it. The next player must form a higher "freak" or "jack," for instance a "9 freak" or a "9 jack," or a "double-freak" or "double jack" from the cards in his hand and in front of him 80 on the table, in order to win the trick from the player immediately in front. Furthermore, if the first player forms a "freak" the next player to win, must also form a "freak" of higher denomination. Or, failing to win, second player may form a "jack," forcing the third player to form a high "jack" to win. The player or side first taking the required number of tricks 85 wins the game, each trick counting 1 point 90 in game, a certain number of points being previously agreed upon as the game total. Obviously the game as above described may be varied in a multitude of details.

In playing a game similar to whist experienced players may bid in turn. If first player wins the play on a 1 or 2 bid, and makes a "freak" to start with, all other players must play a "freak," a higher "freak," or a "double-freak" to take the 100 trick, "jacks" and "double jacks" not counting in the hand at all. If the winning bidder first forms a "jack" the next player must form "jacks" or "double-jacks" to 105 win, the "freaks" or "double-freaks" not being considered.

To play "jacks" the separately shuffled head and tail cards are placed on the table, the head cards in three piles, faces up, and the tail cards in three piles faces down. 110 No account is taken of the number on the cards in this game, the object being to select an exposed card from one of the head cards, and an unexposed card from one of the tail cards to form a complete horse, 115 zebra, etc. Whenever the player succeeds in making a complete "jack" a certain number of cards must be given him by each player. When the cards have all been taken from the table the player having the greatest 120 number of cards is the winner.

It is believed unnecessary to further indicate the different games possible with cards such as described. It is obvious that each card is capable of being combined with another card to form combinations having different values, which values are indicated by the pictorial representations and by the numerical indices carried by the cards.

Modifications of the cards herein dis- 130

closed may be suggested to those skilled in the art, but my invention comprehends all embodiments falling fairly within the scope of the appended claims.

5 What I claim is:

1. A deck of playing cards each of which is provided on its back with a designation classifying it as a head or tail card, each said card carrying on its face a pictorial representation of a half portion of an animal, and being also provided with a symbol denoting the particular value of the card.

10 2. A deck of playing cards each of which is provided on the back with a designation classifying it as a head or a tail card, and carrying on its face a pictorial representation of a portion of an animal, letters comprising a portion of the name of such animal, and additional data denoting the value 20 of the card in playing a game.

15 3. A game device comprising a plurality of cards each bearing on its back a symbol indicating a head card, and a similar number of cards each bearing on its back a symbol 25 indicating a tail card, and a pictorial representation, on the face of each card of each set, which is complementary to a card of the other set in the formation of a complete representation of an animal, when the 30 two cards are juxtaposed.

4. A game device comprising a plurality of cards each bearing on its back a symbol

indicating a head card, and a similar number of cards each bearing on its back a symbol indicating a tail card, the front face 35 of each head card carrying a pictorial representation of the front portion of an animal, together with the letters comprising the front portion of the name of such animal, the front face of each tail card carrying a 40 pictorial representation of the rear portion of an animal, together with the letters comprising the last portion of the name of such animal, substantially as and for the purposes set forth. 45

5. A game device comprising a plurality of cards each bearing on its back a symbol indicating a head card, and a similar number of cards each bearing on its back a symbol indicating a tail card, the front face of 50 each head card carrying a pictorial representation of the front portion of an animal, together with the letters comprising the front portion of the name of such animal, the front face of each tail card carrying a pictorial representation of the rear portion of an animal, together with the letters comprising the last portion of the name of such animal, and additional indicia on the front of each card denoting the value 55 60 of the card in playing a game.

In testimony whereof I affix my signature.

WILLIAM S. BOWMAN.
